UNITED STATES PATENT OFFICE.

ALBERT V. T. DAY, OF NEW YORK, N. Y., ASSIGNOR, BY MESNE ASSIGNMENTS, TO HALL SWITCH & SIGNAL COMPANY, OF NEW YORK, N. Y., A CORPORATION OF MAINE.

COMBINED RAILWAY ELECTRIC TRACTION, TELEGRAPH, AND SIGNAL SYSTEM.

1,125,487.

Specification of Letters Patent.

Patented Jan. 19, 1915.

Application filed September 15, 1906. Serial No. 334,733.

To all whom it may concern:

Be it known that I, ALBERT V. T. DAY, a citizen of the United States, residing at the borough of Brooklyn, city of New York, in the county of Kings and State of New York, have invented certain new and useful Improvements in Combined Railway Electric Traction, Telegraph, and Signal Systems, of which the following is a specification, reference being had therein to the accompanying drawing, forming a part thereof.

My invention relates to electric signaling means for railways, employing rail circuits and periodic current for controlling the signals.

My object is to provide signaling means peculiarly advantageous in its adaptation to railways in which the track rails are also employed as conductors for periodic traction current, or periodic telegraph current, or both, and I have illustrated such an adaptation of my invention in two sheets marked "Left part of Fig. 1" and "Right part of Fig. 1", which are to be read together as one drawing.

In this instance one of the track rails or traffic rails R is continuous and the other traffic rail S is divided into signal blocks or sections by means of suitable insulations interposed in the rail in a well known manner and located at signal stations which I have marked consecutively A, B, C, D, E, F, G, H, I, and J. This embodiment includes two fixed telegraphic stations of the telegraphic system, these stations being marked M and Q in the diagram and being, in this instance, located substantially at the signaling stations E and J respectively.

The current for railway motive power or traction and for the telegraph system, and also electric current for operating all the block signaling apparatus of the system, are supplied from a power station which I have marked P and which, in the illustrated instance, is located at the terminus of the railway track. The system includes a third-rail T adjacent to the railway track and divided into sections by suitable insulations interposed, in the present instance, at the telegraph stations M and Q. The sections into which the third-rail T is thus divided are much longer than the sections into which the signal rail S is divided by its

insulations at the signaling stations. These 55 blocks or sections of the third-rail T will be hereinafter designated as third-rail blocks or sections, or telegraph blocks or sections, in contradistinction to the shorter blocks or sections of the signal rail S. 60

Each insulation in the signal rail S is spanned by an impedance coil such as 3^a, 3^b, 3^c, etc., at the various signaling stations, and the insulations in the third-rail T are similarly spanned by impedance coils 30^m and 65 30^q located substantially at the telegraph stations M and Q; and thereby the signal rail S and the third-rail T are rendered conductively continuous for unidirectional or non-periodic current although the impedance coils effectually isolate the successive rail sections from each other as regards inter-transmission of current components characterized by periodic variation.

The continuous track rail R, and the block 75 signal rail S which is also conductively continuous for unidirectional motive power current, are both employed as return conductors for the motive power or traction current. These track rails are cross-connected by impedance coils such as 2^b, 2^c, 2^d, etc., located midway between successive block signal stations and acting as cross bonds for unidirectional current while at the same time impeding the transmission of 80 periodic current from rail to rail. The unidirectional or direct current traction generator p¹ is, of course, grounded on both the track rails R and S, and delivers current to a line feeder p⁵ extending out along the 90 railway line. The successive sections of the third-rail T are fed by the line feeder p⁵ through impedance coils p², 32^m and 32^q, the first impedance coil p² being located substantially at the power station P and the impedance coils 32^m and 32^q being located respectively at the telegraph stations M and Q. In addition, the successive sections of the third-rail are fed by each other through the impedance coils 30^m, 30^q, etc., which 100 unite such third-rail sections for interchange of unidirectional current.

An alternating current generator p³ is located at the power station P, and delivers alternating current to a transmission line 105 including two conductors p⁶ and p⁷ extending out along the railway line. The block signaling apparatus at the signaling sta-

tions B, C, D, E, F, G, H, I, and J are all the same, wherefore the block signal apparatus at the signaling stations B and C may be described as representatives of the 5 apparatus at the other stations. The signaling apparatus at each station excepting A includes a transformer comprising primary and secondary coils such as 5^c and 4^c respectively, each primary coil being fed 10 from the alternating current transmission line wires p⁶ and p⁷ and each secondary coil being connected with the track rails of the signal block next in the rear. The secondary coil, such as 4^c of each transformer 15 feeds alternating current to the rail circuit of the signaling block next in rear, such rail circuit of the block B C being traceable as follows: from one terminal of the secondary coil 4^c to the advance end of the section B C 20 of the signal rail S, thence rearward through such section of the signal rail S to the rear end of the block B C and thence through the alternating current relay magnet 7^b and the condenser 6^b, both included 25 in the signal apparatus B, and from the condenser 6^b to the continuous track rail R and thence forward through such track rail to the advance end of the block B C and back to the opposite terminal of the sec- 30 ondary coil 4^c. Current from the secondary coil 4^c traverses the foregoing rail circuit when there is no train or railway vehicle present in the block B C, and, excepting leakage current which passes from rail to 35 rail through the ground and ties, substantially all of the alternating current from such secondary transformer coil 4^c traverses such rail circuit, because such alternating current is effectually impeded or refused by 40 the impedance coils 3^c, 2^c and 3^b.

The condenser 6^b included in the foregoing rail circuit and its relationship to the alternating current relay 7^b, constitute an important feature of my invention whereby 45 very important results are attained, as will be described shortly hereinafter.

If a train or railway vehicle were present in the block B C, the alternating current from the secondary coil 4^c of the transformer would be short-circuited by the 50 wheels and axles of the train or vehicle and pass freely from one track rail to the other, thus being shunted around the relay 7^b so as to effectually prevent the relay from 55 being energized. Under these conditions the contact finger 8^b of the relay is held by any suitable retractive force out of engagement with its coöperating contact stop 9^b, so as to maintain the signal semaphore 10^b 60 in its danger position indicating that the block B C is occupied. But when there is no train present in the block B C the rear track relay 7^b of such block is energized by alternating current flowing through the cir- 65 cuit already traced, so as to maintain its

contact finger 8^b in contact with the coöperating stop 9^b and thus maintain a flow of current through the semaphore-actuating-or-retaining electric-mechanism included in series with the contacts 8^b, 9^b in a local 70 branch circuit bridged across the alternating current line conductors p⁶, p⁷. Thus the signaling apparatus at the signal station B always indicates the condition of the block B C, the semaphore 10^b of such signaling 75 apparatus being known as a home signal.

To those schooled in the art it will be apparent how the signaling apparatus at any one or more of my signaling stations can be supplemented by an additional semaphore 80 controllable by the condition of the signal block second in advance thereof, such an additional signal semaphore being known as a distant signal. Such distant signals and the additional circuits or apparatus necessary 85 to control them have been omitted from my drawings simply for the sake of greater clearance in the illustration of the more important rudiments of my invention.

The capacity of the condenser 67 and the inductance of the alternating current relay 77 are relatively adjusted for resonance with the alternating or periodic current employed in the block-signaling rail circuit. This adjustment discharges a most unique 90 and valuable function which can most aptly be explained by a comparison with the old style unidirectional-current or battery-current block signaling systems well known in the prior art. In these battery systems it 100 has been customary to connect a battery with the track rails at the advance end of the signaling block and to connect what is known as the rear track relay with the rails of the same signaling block at the rear end 105 of the block. When no train is present in the signaling block the battery current flows from the advance end of the block through the rails and through the rear track relay so as to clear the signal controlled by 110 such relay at the rear end of the block. Obviously, in such prior systems, the signaling current encounters only the ohmic resistance of the relay at the rear end of the rail circuit, but even so, it has been found 115 that when the signaling block is very long or when the ground and rail ties are very wet, leakage from rail to rail through the ground and ties is so great as to effectually shunt current from the rear track relay so 120 that it will not clear the signal when the block is clear, unless a battery of considerable strength is employed. Now, when we apply an alternating current to the rails at the advance end of the signaling block, in lieu of a unidirectional current, the foregoing difficulty is greatly augmented because 125 added to the ohmic resistance of the relay, we have its inductive resistance, so called, or its counter E. M. F. of self-induction, so 130

that the opposition to the flow of the alternating current through the relay is much greater than the opposition to flow of unidirectional current, although the leakage path 5 through the ground and ties conducts the alternating current with equal facility since such leakage path is a substantially non-inductive branch. The conditions make it exceedingly difficult to operate a rear track relay through a traffic-rail circuit with an alternating current when the signaling block is long or when it is subjected to wet weather, unless an exceedingly strong current is delivered to the rail circuit to make good the 10 excessive leakage. But my provision of capacity adjusted relative to the track relay in resonance with the block signaling current attains that same relationship of impedances through the track relay and 15 through the leakage branch from rail to rail, which relationship is attained in the old battery block signal circuits; and by means of my invention therefore it is possible to clear a block signal through a traffic- 20 rail circuit positively and reliably and without employing an excessive signal-clearing current at the advance end of the rail circuit to make up for the enormous leakage from rail to rail.

30 Another important function and result of the adjustment of my condenser and track relay in resonance with the block signaling current, is the saving in the expense of the block-bonding impedance coils such as 3^a, 3^b, 35 etc., employed to connect the adjacent sections of the block signaling rail S, and a saving in the resistance losses in the return circuit of the motive power current, and also a saving in the expense of the cross-bonding 40 impedance coils such as 2^b, 2^c, etc. The resonant adjustment of the rear track relay and its condenser, by reducing the impedance through the relay branch to the ohmic resistance of such branch, makes it possible 45 to operate the track relay with a much lower voltage of block signaling current than the voltage which would be required in the absence of such resonant adjustment. By thus reducing the block-signaling difference 50 of potential between opposite rails required to operate the block signal, my resonant adjustment of relay and condenser makes it possible to employ block-bonding and cross-bonding impedance coils of much lower impedance and hence much less expensive in 55 cost of construction and also less wasteful of motive power energy in the return path of the motive power current. Since these block-bonding and cross-bonding impedance 60 coils are employed to prevent passage of block signaling current between adjacent sections of the signal rail S and between such signal rail and the continuous rail R, it is obvious that the more the voltage of 65 the block signaling current is reduced, the

more we may reduce the size and expense of the impedance coils without impairing their foregoing functions.

Another important function and result of the adjustment of my condenser and track 70 relay in resonance with the block signaling current, is the selective responsiveness of such relay to the alternating or periodic current of that particular frequency employed for clearing its particular block signals, and in discrimination against all other alternating or periodic currents such as the alternating or periodic currents employed in my telegraph system, or periodic currents which might be employed in the traction system in lieu of the unidirectional current employed in that embodiment of my invention which I have specifically illustrated. In the event of an accidental break in one of the track rails, which act as conductors for 85 the telegraph current and the traction current as well as for the block signal current, or in the event of some other derangement of the system, the telegraph current or an alternating or periodic traction current if 90 such were employed for motive power, might stray from rail to rail through the block signal relay 7^b, and in the absence of preventative measures might operate the relay to clear its signal at some time when the 95 signal should remain in its danger position.

My invention contemplates the employment of block signaling currents to operate a given relay such as 7^b, having a periodicity distinctly different from the periodicities or 100 frequencies of all other periodic currents employed in my system. Should a current higher in frequency than such distinct block signaling current attempt to pass through the relay 7^b, it would be strongly impeded 105 by the counter E. M. F. of the relay which, at such higher frequency, would be only partly neutralized by the counter E. M. F. of the condenser; and should the relay be subjected to a current lower in frequency 110 than the distinct block signaling current to which it resonantly responds, such current of lower frequency would be effectually opposed by the counter E. M. F. of the condenser which, at such lower frequency, 115 would be only partially neutralized by the inductance of the relay. Thus the relay branch from rail to rail refuses to conduct in substantial degree any current other than the particular block signaling current to 120 which the relay responds in resonance.

In addition to the fixed telegraphic stations M and Q of the telegraph system, I have illustrated three moving telegraph stations K, L, N, these moving telegraph stations of the telegraph system being carried on moving trains or railway vehicles, for 125 which reason the three stations will be hereinafter for convenience referred to as the trains K, L, N. The trains K and L are 130

represented in the telegraph block P M, that is to say, they are represented in that portion or section of the railway track extending from the power station P to the fixed telegraph station M, and through which railway block the first third-rail section extends. The train N is represented in the telegraph block M, Q, extending from the telegraph station M to the telegraph station Q and comprising the third-rail section M, Q. The wheels and axles of the trains K, L, and N, are represented respectively at 2^k, 2^l, and 2ⁿ, showing that these trains are located respectively in the signaling blocks 15 A, B, C, D and G, H. The trains take current from the third-rail T through their respective third-rail shoes 5^k, 5^l, and 5ⁿ, such shoes being connected with the conductors 4^k, 4^l, and 4ⁿ, leading to the apparatus on 20 the respective trains, and the apparatus on each train is connected with the axles and wheels of the train by means of conductors such as 3^k, 3^l, and 3ⁿ on the three trains respectively.

25 Each train receives motive power or traction current from the third-rail through a circuit which may be traced, for example, on the train K, as follows: from the third-rail T, through the third-rail shoe 5^k, conductor 4^k, fields 7^k of the train motor, armature 6^k of the train motor, conductor 3^k and wheels and axles 2^k to the traffic rails R and S which, as already pointed out, constitute a return circuit to the power station. Each 30 train carries also a rotary converter or motor-generator adapted to convert current from the traction generator at the power station P into current suitable for sending telegraphic communications or other signals from the train to a point outside the train. The motor-generator in this instance comprises a direct current motor armature and two alternating current generator armatures. Considering, for instance, the apparatus 35 of the train K, it will be noted that the traction current passes through the shoe conductor 4^k, thence through the fields 9^k of the motor-generator, motor armature 8^k of the motor-generator, and thence to the grounded conductor 3^k. The field winding 9^k may be employed to excite not only the motor-armature 8^k but also the two alternating current generator armatures 10^k and 14^k. These generator armatures 10^k and 14^k are 40 connected in respective parallel branch circuits leading from the shoe conductor 4^k to the grounded conductor 3^k, through respective signal keys 13^k and 17^k and their stationary contact members 12^k and 16^k and the condensers 11^k and 15^k and the armatures 10^k and 14^k connected in series with such condensers respectively and with their signal keys. Each train carries also two receiving instruments such as the receiving sounders 18^k and 24^k of the train K, connect-

ed in parallel branch circuits between the shoe conductor 4^k and the grounded conductor 3^k. These parallel sounder branches include condensers 19^k and 25^k in series with the sounders 18^k and 24^k respectively, and 70 include also respective controlling switches 20^k and 26^k likewise in series with the sounders and their respective condensers. The sounders include respective armatures 21^k and 27^k normally held by suitable retractile 75 springs 23^k and 29^k against suitable back-stops so that the armatures are in position to be attracted toward their respective sounder magnets by sufficient magnetization thereof.

80 The fixed stations M and Q of the telegraph system comprises apparatus corresponding substantially to that carried by the moving trains, excepting the traction motors, third-rail shoes and the wheels and axles of the trains, which are, of course, omitted at the fixed stations. At such fixed stations M and Q, the grounded conductors 3^m and 3^q are connected directly with the continuous track rail R, and the conductors 4^m and 4^q, corresponding to the shoe conductors of the trains, are connected directly with respective telegraph sections of the third-rail T.

85 Not all the foregoing apparatus of the telegraph system is essential to the rudimentary operation of my invention, nor is it essential that the apparatus shall be embodied in the specific forms illustrated and described, since any equivalent may be substituted for the sounder or for the condenser or for any other element. For instance, to exemplify one operation of my invention, it may be assumed that all the apparatus on the train K is dispensed with excepting the sounder 24^k, its condenser 25^k, its sounder-controlling switch 26^k, the conductor 4^k leading to the third-rail shoe, the grounded conductor 3^k leading to the wheels and axles, and the traction motor 6^k. Now the traction 90 motor 6^k will receive motive power current passing in the usual way from the third-rail through such motor and to the traffic rails included in the return path of the current; but the traction current, which in this instance is a unidirectional current, will not pass through the sounder 24^k because its condenser 25^k will not transmit such traction current. The condenser 25^k will, however, transmit a periodic or alternating 95 telegraphic or signaling current to and through the sounder 24^k; whereby the train K may receive signals or telegraphic intelligence from another station, for instance, from the fixed station M of the telegraph system, 100 through a circuit traceable as follows: From one brush or terminal of the alternating current generator armature 14^m of the motor-generator at the station M, through the condenser 15^m, contact stop 16^m, signaling 105

or telegraphic key 17^m, conductor 4^m leading to the third-rail section P M, thence through such third rail section to the shoe 5^k carried by the train K, and thence through the shoe 5 conductor 4^k on such train, the sounder-controlling switch 26^k, condenser 25^k, sounder 24^k, grounded conductor 3^k, wheels and axles 2^k, and continuous track rail R to the grounded conductor 3^m at the station M and 10 through such grounded conductor 3^m back to the opposite brush or terminal of the alternating current generator armature 14^m. The alternating current thus delivered by the generator armature 14^m, through the 15 foregoing circuit and its receiving sounder 24^k, may be of such high frequency that the sounder armature 27^k will not be recovered by its retractile spring 29^k, between successive current pulsations, but will be held 20 down against its stop 28^k so long as the sending key 17^m is pressed against its contact stop 16^m.

Obviously, by the foregoing or equivalent means, telegraphic intelligence or other signals may be transmitted to the train K through its sounder 24^k, or through any signal receiving device equivalent thereto in the broad aspect of my invention. And such signals may be transmitted in the foregoing

30 instance, regardless of the relationship of inductance and capacity in the sounder and its condenser 25^k, providing only that the E. M. F. of the telegraphic current is high enough to force through the condenser and 35 the sounder a sufficient current to effectually magnetize such sounder and attract its armature. Therefore, my broad invention is in no wise limited to a resonant adjustment or to any other adjustment of inductance and capacity in the sounder or equivalent device and its condenser, although a resonant adjustment of such inductance and capacity is highly advantageous in various ways. For instance, if an alternating traction current be employed in lieu of a unidirectional traction current, the sounder and

45 its condenser may be adjusted in resonance with a particular signaling current of the telegraph system so that the sounder will 50 respond readily to such particular current while its armature and retractile spring will be adjusted to avoid any response to the alternating current of the traction system which will flow with comparatively weak 55 intensity against the unbalanced counter electromotive forces of inductance and capacity which are not adjusted in resonance with such traction current. Also when two sounders are provided, such as the 60 sounders 24^k and 18^k on the train K, in order to receive simultaneously two messages or signals from one or more points outside the moving train, each sounder and its respective condenser may be ad- 65 justed relatively to each other in resonance

with one of two alternating or periodic currents of different frequencies. In this instance a given sounder will resonantly respond to its own particular periodic or alternating current while its armature will be adjusted to avoid response to the periodic current which resonantly operates the other sounder and which will flow in comparatively weak degree through the given sounder. Thus, distinct simultaneous 70 messages or signals may be received on one of the moving trains or at one of the fixed stations of the telegraph system. The simultaneous messages thus received at one station of the telegraph system may emanate 75 from two other stations of the system or may both emanate from one other station of the system, and in order that two messages may be simultaneously sent from one station I have provided each station of the 80 telegraph system with means for generating and controlling two periodic currents of different frequencies adapted for transmission of intelligence to one or more different stations of the system, such means being embodied, in the present instance, in the 85 motor-generators each having two generator armatures controlled by respective sending keys.

As an advantageous arrangement of apparatus it is suggested that all the sounders uppermost in the diagram of the telegraph system, to wit, the sounders 24^k, 24^l, 24^m, 24ⁿ and 24° may be adjusted with their respective condensers in resonant responsiveness to 90 periodic current of one particular frequency which may be commonly produced by all of the alternating current generator armatures which are uppermost in the diagram, to wit, the armatures 14^k, 14^l, 14^m, 14ⁿ and 14°; 100 while all the sounders lowermost in the diagram may similarly respond to a common periodic current which may be commonly produced by all the alternating current generator armatures which are lowermost in 105 the diagram.

When the operator at one station is sending with one of his sending keys, the sounder at his own station which is responsive to such sending key may be cut out of circuit to economize the sending current. For instance, if the operator at M is sending a message with his sending key 17^m, he may open his sounder controlling switch 26^m so as to cut out his sounder 24^m and 110 avoid waste of the sending current controlled by the key 17^m, which sending current will then proceed along the third-rail section P M and along the continuous track rail R to those sounders resonantly responsive to such current on one or both of the trains K and L. If it is desired to send this message simultaneously to both trains K and L, the operators on both such trains 115 will leave their sounder controlling switches 120 125 130

26^k and 26^l closed so as to maintain in circuit their respective sounders 24^k and 24^l, both resonantly responsive to such current. But if it is desired to send such message to 5 the train K only, then the operator on the train L will open his sounder-controlling switch 26^l. Now, it is quite apparent that while the foregoing message is being sent by the key 17^m at the fixed station M, another 10 message may be sent from such fixed station by the key 13^m, and will operate one or both of the sounders 18^k and 18^l on the trains K and L, accordingly as one or both of these sounders are included in circuit 15 through their respective sounder controlling switches 20^k and 20^l. Or, while the first mentioned message is being sent through the sending key 17^m at the station M, the sending key 13^m at such station may be left 20 open and such station may receive a simultaneous message from either of the trains K or L, for instance, from the train K whose operator will send out the message through his sending key 13^k, thus delivering to the 25 third-rail section P M and to the continuous track rail R, a periodic current which will effect resonant response of the sounder 18^m at the fixed station M, and which, incidentally, will also effect resonant response 30 of the sounder 18^l on the train L, if the operator of such train has closed his sounder controlling switch 20^l to receive such message from the sending key 13^k on the train K.

35 Such examples of the use of my system might be largely multiplied but it is sufficient to state that a given sending key can be employed to deliver messages simultaneously to one or all of the stations of the 40 telegraph system which are included in one third-rail section or telegraph section in common with such given sending key; and that any other sending key included in the same telegraph block or section and controlling 45 a periodic current of different frequency may be similarly employed at the same time. However, if it were desired to send separate messages to a large number of trains all operating on one third-rail section, a large number of different periodic 50 currents would have to be employed, and to avoid this necessity is one object which I have in view in dividing the third-rail into separate telegraph blocks or sections, each 55 telegraph block being restricted to such length of railway track as will be ordinarily occupied by a comparatively small number of separate railway trains or vehicles. Since the third-rail sections are substantially 60 isolated as regards interchange of the periodic telegraph currents, such currents of the same frequency may be employed without interference in adjacent third-rail sections or blocks, the telegraph 65 current applied to one third-rail section be-

ing not effectually transmitted to the adjacent third-rail sections. Thus the operator at the station Q may employ his sending key 17^a to transmit intelligence through the medium of the sounder 24ⁿ on the train N, 70 without affecting the sounders 24^k, 24^l, and 24^m, responsive to telegraph current of the same frequency but located in a different third-rail section. It will be noted that the condensers such as 11^k and 15^k in series with 75 the generator armatures of the motor generators of the telegraph system, prevent unidirectional motive power current from passing through such generator armatures.

If desired each telegraph block or section of my system may include a fixed station attended by an operator in constant communication with the train despatcher through the medium of the ordinary train-despatching telegraph system, and thereby 80 the train despatcher will be in constant communication with every train on his division. A train may be recalled after it has passed a railway station or after passing a railway station the train may receive orders to stop and take an isolated siding to permit another train to pass. Wrecks and stoppages of the trains may be immediately reported from isolated points, and in short many great advantages can be realized from 85 the use of my invention.

It will be apparent that an overhead trolley wire may be employed in lieu of a third-rail. Since alternating current is a well known substitute for unidirectional traction 90 current, it may be noted that if the traction generator p¹ is to deliver an alternating current it will be well to omit the impedance coils p², 30^m, 32^m, 30^q, 32^q, etc., and feed the third-rail or trolley wire direct from the 95 traction generator without any interposition of impedance coils which would more or less impair the transmission of the alternating traction current. In this event the third-rail or trolley wire will constitute a 100 single continuous telegraph conductor such for instance as exemplified in the third-rail section P M with the impedance coil p² omitted. All moving and fixed stations of the 105 telegraph system will then commonly 110 operate upon such single continuous motional telegraph conductor, it being only necessary to employ telegraph current differing in frequency from the alternating 115 traction current and effecting resonant or 120 selective response of the telegraph sounders or receiving instruments. Indeed, as to the broad aspect of my invention, it is sufficient 125 that the traction current and the telegraph current or currents be different in character and, although I have particularly described the employment of unidirectional traction current and alternating telegraph current, I do not wish to be limited to this particular choice or arrangement of currents since it is 130

perfectly obvious that the arrangement may be reversed or otherwise modified.

What I claim and desire to secure by Letters Patent is:—

- 5 1. A railway signaling system comprising a signaling apparatus and a signaling circuit in control of the signaling apparatus and including the traffic rails of the railway track and a source of signaling current characterized by a periodic variation of distinctive frequency and including inductance and capacity adjusted substantially in resonance with the periodic variation of the signaling current.
  - 10 2. A railway electric signaling system comprising a section of railway track, a source of periodic signaling current connected with the rails of the section, a self-inductive electro-translative device and condenser arranged to receive electrical energy from the rails of the section and arranged and adjusted so that the condenser will oppose and substantially neutralize the counter electro-motive-force of self-induction in the translative device, and signaling apparatus controllable by the translating device.
  - 15 3. A railway electric signaling system comprising a section of a railway track, a
- source of periodic signaling current arranged to deliver such current to the rails of the section, a self-inductive electro-translative device and condenser connected together and relatively adjusted substantially in resonance with the frequency of the periodic signaling current and arranged to receive electrical energy of such frequency from the rails of the section, and a signaling apparatus controllable by the electro-translative device.
4. A railway electric signaling system comprising a section of a railway track, a source of periodic signaling current arranged to deliver such current to the rails of the section, a self-inductive electro-translative device and a condenser connected in series across the rails of the section and relatively adjusted substantially in resonance with the frequency of the periodic signaling current, and signaling apparatus controllable by the electro-translative device.

In testimony whereof I have affixed my signature in presence of two witnesses.
